MATTRESS TUFTING MACHINE

Joseph W. Droll, Chicago, and Alex H. Olson,
Evanston, Ill., assignors to Droll Patents Corporation,
Chicago, Ill., a corporation of Delaware

Application April 17, 1935, Serial No. 16,790

13 Claims. (Cl. 112—3)

The invention relates to tufting machines, more particularly to the type in which the mattress is placed on a laterally movable table for successive insertion of rows of tufts into the mattress.

The objects of the invention are: to provide an improved tufting machine; in which members are adapted to compress a mattress for a row of tufts, a row of needles are provided for inserting tufting ties simultaneously through the mattress and the mattress-supporting table is movable or slideable transversely to position it for successively inserting the rows of tufts; in which one of the compressor members carries a row of needles for inserting the tufting which are movably mounted so that ties can be inserted at intermediate points for different types of tufting; in which the needles for inserting a row of tufting ties through the mattress are resiliently mounted so that in event one of them is obstructed by a spring in a mattress, breakage of the needle will be prevented; in which a gang of needles for a row of tufts is adjustably mounted on a compressor member so the spacing between them can be readily varied to correspondingly varying the spacing between the tufts; which is simple in construction and easily and readily operable to tuft mattresses; and other objects which will appear from the detail description.

The invention consists in the several novel features which are hereinafter set forth and are more particularly defined by claims at the conclusion hereof.

In the drawings:

Fig. 1 is a central longitudinal section of a machine embodying the invention.

Fig. 2 is a horizontal section on line 2—2 of Fig. 1.

Fig. 3 is an end elevation.

Fig. 4 is a vertical section showing the compressor-operating mechanism.

Fig. 5 is a perspective of a portion of the upper compressor.

Fig. 6 is a perspective of one of the tufting needles and its carrying block.

Fig. 7 is a perspective of a portion of the lower compressor and needle support.

Fig. 7a is a section on line 7a—7a of Fig. 8.

Fig. 8 is a vertical section of one end of the machine, the compressors being shown in position to compress the mattress.

Fig. 9 is a section on line 9—9 of Fig. 8.

Fig. 10 is a perspective of the slide on which one of the needles is mounted for movement independently of the remaining needles of the series.

Fig. 11 is a perspective of a cap-block secured to slide with the base of said slide.

Fig. 12 is a section on line 12—12 of Fig. 8.

Fig. 13 is a section on line 13—13 of Fig. 8.

Fig. 14 is a section on line 14—14 of Fig. 8.

The invention is exemplified in a tufting machine comprising a suitable supporting frame on which is carried a freely transversely movable mattress-supporting table, upper and lower compressors each mounted for movement to and from a mattress on the table and a gang of needles movable with one of the compressors for inserting the tufting-ties therethrough.

The supporting frame comprises a pair of rigid cast standards 20 extended transversely at their lower ends to form feet for stably supporting the frame and a pair of longitudinal angle bars 21 fixedly secured to the standards adjacent their lower ends and serving to connect the standards to form a rigid supporting structure for the several operating parts of the machine.

A transversely movable mattress-supporting table or frame 22 comprises longitudinal angle-bars 23 fixedly secured to end bars 24, intermediate transverse bars 25 fixedly secured to the bars 23, transverse supporting boards 26 for the ends of the mattress and upstanding end bars 27 whereby the mattress will be positioned longitudinally on the table. All of these bars are rigidly connected together to form a frame or table for supporting a complete mattress. This supporting frame is freely movable transversely by the operator to successively bring different lines of the mattress into tufting position. End bars 24 each fit between a pair of lower rollers 28 and rollers 29 which are journaled on standards 20, and are provided with peripheral grooves into which the lower and upper margins of the bars 24 are confined. To insure true and free rectilinear movement of the mattress-supporting table, a rack-bar 30 is fixed to the outer side of each bar 24. Each rack-bar 30 meshes with a gear 31 formed on one of the rollers 28 and a shaft 32 extends between and is keyed to rotate with said gears and rollers. The remaining guide-rollers 28 and 29 are journaled on studs 33 which are fixed in the standards 20. The ends of shaft 32 are journaled in bearings 34 fixed to the inner side of standards 20. The bars 24 project beyond the bars 23 at the front and rear of the frame 22 and the projecting ends are rigidly supported by corner brackets 35 between bars 23 and bars 24. These extensions support the table when it is shifted into position for tufting the rows adjacent the sides of the mattress. Stops 36

30

35

40

45

50

55

adapted to engage the standards 20 are secured to the bars 24 to limit the transverse movement of the mattress-supporting frame.

This construction exemplifies a freely and reciprocally movable frame or table for supporting a mattress and by which the mattress can be successively shifted into position for inserting rows of tufting ties through the mattress.

Upper and lower compressors are provided to compact the mattress along a longitudinal line for the insertion of a longitudinal row of tufting ties at a single operation. The upper compressor comprises a pair of supporting bars 40 having their ends fixedly secured to brackets 41. These brackets are provided with lugs 42 which are slidable on vertical guide-rods 43 which have their upper and lower ends anchored in the standards 20. Brackets 41 travel in vertical slots 44 in said standards. A pair of compressor or mattress-engaging bars 45 are supported by hangers 46 and are secured thereto in spaced relation from each other by bolts 47 and sleeves 48 between bars 45 and hangers 46. The longitudinal space between bars 45 is provided for the tufting needles and ties. The inner upper portions of bars 45 are bevelled as at 49 to provide access to the space between the bars in applying the tufts to the ties after the needles with the ties have passed through the mattress. The lower compressor and needle supporting means comprise a pair of supporting bars 50, which at one end are fixed to a stub-shaft 51 which is slidably fitted in a cross-head 52 and at the other are slidably supported by a stub-shaft 51^a. Cross-head 52 is provided with laterally projecting lugs 53 which are slidable on the guide rods 43, so that the blocks and parts supported thereby can rise and fall in the standards and relatively to the mattress-supporting frame.

40 A row of lower needle and compressor units for a complete longitudinal line of tufts for a mattress are mounted to reciprocate vertically under the mattress. Each of these units comprises a carrier-block 55 for a needle 78 and a 45 pair of upstanding compressor studs 57 arranged transversely of the needle. These studs are vertically aligned with the upper compressor-bars 45 so that when the compressors are brought together, the mattress will be compressed between 50 the studs and the bars, with spaces for insertion of the ties between the bars.

Mechanism for simultaneously reciprocating the compressors to compress and release a mattress and force the needles through and out of the mattress comprises a longitudinal shaft 59 which is journaled in the standards 20; a connection between each end of said shaft and one of the brackets 41 at the ends of the upper compressor supporting bars 40 consisting of a crank 60 or arm 60 fixed to rock with shaft 59 and a link 61 pivoted to said crank and pivotally connected by a pin 62 which is held in the bracket 41; and a connection between each end of shaft 59 and one of the cross-heads 52 whereby the supporting shafts 51, 51^a and bars 50 for the lower compressor are carried, consisting of a crank or arm 63 fixed to shaft 59 so as to rock therewith and a link 64 pivoted to arm or crank 63 and at 65 to cross-head 52. At one end of the machine a 70 foot lever or pedal 66 is pivoted at 67 to one of the standards 20 and is connected by a wrist-pin 68 which extends through a slot 69 in the lower compressor member to a crank 70 which is fixed to one end of the shaft 59. Lever 66 is provided 75 at either end with a foot piece 71 so that by

depressing one of them, crank 70 will be swung to rock shaft 59 to vertically spread the compressor supporting members apart and by depressing the other end of the lever, the shaft 59 will be reversely rotated to shift the compressors toward one another. At the other end of the machine a pedal or foot lever 72 is pivoted at 73 to one of the standards 20 and has fixed thereto a gear 74 which meshes with a pinion 75 which is fixed to shaft 59, for rocking shaft 59 in either direction to correspondingly operate the compressors. Lever 72 is also provided with a foot piece 76 at its front and rear ends. Lever 72 and the gearing 74, 75 are adapted to be operated while the operator is at one end of the table, and lever 66 while the operator is at the other end, so that the compressors can be operated from either end. The upper ends of links 61 are adjustably connected to brackets 41 by means of a series of holes 77 for pins 62. By setting the pins in different holes, the lowering of the upper compressor with respect to the mattress on the table and the range of travel of said compressor may be varied to give the desired compression according to the thickness of the mattress.

Each block 55 and block 55^a has mounted thereon a needle 78 which is adapted to penetrate and pass through the mattress from the bottom to draw a tie through the mattress. This needle is provided with a notch 79 for receiving the upper end of a looped tie, which carries a tuft at its lower end, so that when the upper end of the tie has passed through the compressed mattress, it may be unhooked from the needle and the upper tuft connected thereto before the needle is retracted. Each needle 78 is disposed between an associated pair of tufting studs 57 and is adapted to pass between the spaced upper compressor bars 45. In practice it has been found that if the ties for a longitudinal row of tufts are simultaneously inserted through the mattress, one or more of the needles may encounter a spring or springs of an inner spring mattress and to prevent breakage of the needle when that occurs, each is yieldingly held in its bracket 55. Each needle 78 is secured in a stem 80 which is vertically slidable in its carrying block and is provided with a notch 81 to receive the inner curved end of a plunger 82. A coil spring 83 between the plunger and a screw plug 84 which is threaded to a lug projecting from one side of each of said blocks presses the rounded end of the plunger into the notch 81 so that when the needle encounters a spring, the plunger will permit the needle to slide downwardly in bracket 55. Each needle 78 is adjustably secured in its stem 80 to adapt it to pass through mattresses of different thicknesses. A stem 85 on the plunger 82 extends through the plug 84 so that when desired, the stem 80 may be manually released when it is desired to withdraw, replace or adjust the needle. A knob 86 is provided at the lower end of each stem 80 by which the stem and needle carried thereby may be pushed upwardly into its operative position after it has been lowered. This construction exemplifies means for yieldingly carrying the needles for inserting ties through the mattress which will yield when any one of the row of needles encounters a spring in the mattress.

The operation for "biscuit" tufting will be as follows: the needles will be positioned as shown in full lines in Fig. 1. The mattress to be tufted will be placed on the table 22 between the end boards 27. Markers 110 are provided on these end boards to indicate the longitudinal lines

along which the tufts are to be applied. The mattress is placed on the table while the compressors are spread apart. The table 22 is then shifted to bring the first line to which the tufts are to be applied between the upper and lower compressor members. Tufting ties each with a button attached to its lower end, will then be hooked into the notches 79 of each of the needles 78 under the mattress. The operator will then, 5 by depressing one end of foot lever 69, operate shaft 59 to operate links 64 to raise the lower compressor supporting bars 50 and to lower the upper compressor supporting bars 40. During this movement, the mattress will be compressed 10 between bars 45 and studs 57 and the needles 78 will penetrate and pass through the compressed 15 portions of the mattress.

Next, the tufting loops will be unhooked from the needles 78 and tufting buttons or tufts will be attached to the upper ends. The operator will 20 then shift one of the pedals to lower the supporting bars 50 and to raise the supporting bars 40, which will release the compression of the mattress and withdraw the needles therefrom. After 25 this operation has been completed, the table can be moved over to one side, to give access to the needles for hanging another series of ties thereon. The table with a mattress thereon will then be shifted transversely to bring the next of the 30 markers 110 in line with the compressors for the insertion of the next rows of tufts.

All except one of the compressor and needle units comprise a block 55 which is grooved to receive the bars 50 and each of these blocks is 35 secured on said bars by a pin 56 so that the blocks can be adjusted longitudinally for different spacing between the tufts of a row. The block 55^a of the compressor and needle unit at one end of the machine is carried by a slide 90 which is secured by bolts 91 to the inner end of a stub- 40 shaft 51^a, and to which the bars 50 which carry the blocks 55 are slidably connected. Stub-shafts 51^a and 51 are suitably locked against rotation in the cross-heads 52. The blocks 55, 55^a and the needles and compressor-studs carried thereby 45 are movable longitudinally so the needles can be shifted to insert alternative lines of tufts at longitudinally intermediate points of the other lines of tufts. For example, in "diamond" tufting a mattress, the alternate rows have more tufts 50 than the intermediate rows. The needles and compressor-studs are conjointly shifted longitudinally and one of the needles and pair of studs at the end of the row is shifted relatively to the other needles to bring it beyond one end of the 55 mattress and render it inoperative when the line requires the lesser number of tufts and operative for a line of the greater number. To shift all of the needles and compressor-studs conjointly and to impart to the block 55^a sufficient additional 60 travel to render inoperative and operative for alternate line of tufts, the block 55^a which carries the needle at one end and its associated studs 57 is mounted to move with slide 90 and shaft 51^a and a lost-motion connection is provided between 65 the slide 90 and the supporting-bars 50 for blocks 55. The slide 90 is provided with guide grooves 92 for the bars 50 and a cap 93 also provided 70 for the upper margins of bars 50, is fixedly secured by bolts 91 to the shaft 51^a and slide 90. Slide 90 is also held in connected 75 sliding relation with bars 50 by a grooved cap 95 which is secured by a vertical bolt 96 to the inner end of slide 90. The block 55^a is adjustably mounted on the slide 90 by bolts 97 and 75 grooved plates 98 to permit adjustment of the

needle in the slide 90 for varying the spacing between the needle on block 55^a and the remaining needles. The endwise travel of bars 50 is limited by the cross-heads 52. A handle 99 is secured to the outer end of shaft 51^a. A handle 100 at the other end of the machine is connected by a bar 101 to the slide 90. The relative movement between slide 90 and bars 50 is limited by a stop-pin 102 fixed to the slide and abutments 103 and 104 fixed to one of the bars 50. 10

In operating the machine for "diamond" tufting, the handle 100 is moved into the position shown in full lines in Fig. 1. The entire series of six needles will then be operative. When the next line of five ties is to be inserted, the handle 100 is pushed inwardly, which will initially move the slide 90 and the carrier 55^a, with the needle and compressor studs supported thereby, to the left, independently of the blocks 55 which are secured to the bars 50. When the pin 102 strikes the abutment 103 on one of the bars 50, the further inward movement of the handle 100 will cause the pin, by reason of its engagement with abutment 103, to conjointly move the entire series of carriers to the left. This will bring the block 55^a 25 so that the needle and compressor-studs carried thereby will clear the mattress, and will be disposed outwardly of the end-boards 27 on the mattress-table when the cross-heads 52 are raised, and the remaining needles carried by blocks 55 will be equi-distantly spaced for tufting at points longitudinally midway between the line of tufts last made. When the succeeding line of tufts is to be inserted, the operator will pull the handle 100 of the machine outwardly. The slide 90 will initially move to the right independently of the bars 50 until the pin 102 strikes the abutment 104 on one of the bars 50 and thereafter 30 all of the needle and compressor-stud carriers will be conjointly shifted to bring all of the needles into operative position for the next line of tufts. This exemplifies means for shifting the needles and compressor-studs for alternative rows of tufts by which they may be conjointly shifted with sufficient additional travel of one 35 of the end needles to alternately render it operative and inoperative by a single operation of one 40 of the handles. 45

The operator may conveniently work from either side of the machine so that it is not necessary to reach from one side of the mattress to the other in applying the tufts to the needles and the tufts to the ties after they have been inserted through the mattress. 50

The invention exemplifies a tufting machine 55 which facilitates the work and by which a complete longitudinal row of tufts can be simultaneously inserted at one operation. Also one in which the operator may conveniently adjust the machine for "diamond" tufting or "biscuit" tufting. Also one in which provision is made for preventing breakage of the needles in the event that any one of a row encounters a spring in a mattress. The machine is simple in construction and facilitates the work of the operator in tufting. 60 65

The invention is not to be understood as restricted to the details set forth, since these may be modified within the scope of the appended claims, without departing from the spirit and scope of the invention. 70

Having thus described the invention, what we claim as new and desire to secure by Letters Patent is:

1. In a tufting machine, the combination of a 75

- supporting structure, a mattress-supporting frame mounted on the structure to move horizontally and rectilinearly, upper and lower reciprocable compressors carried by the structure and adapted to compress the mattress on the frame for the insertion of a row of tufting ties, a row of needles reciprocable with one of the compressors, for simultaneously inserting a row of tufting ties into the mattress on the frame, and a common reciprocable support for said needles and the compressor movable therewith.
2. In a tufting machine, the combination of a supporting structure, a mattress-supporting frame mounted on the structure to move horizontally and rectilinearly, upper and lower reciprocable compressors carried by the structure and adapted to compress the mattress on the frame for the insertion of a row of tufting ties into the mattress, a row of needles reciprocable with one of the compressors, and means for slidably shifting the row of needles into different positions relatively to a mattress on the frame.
3. In a tufting machine, the combination of a supporting structure, a mattress-supporting frame mounted on the structure to move horizontally and rectilinearly, upper and lower reciprocable compressors carried by the structure and adapted to compress the mattress on the frame for the insertion of a row of tufting ties into the mattress, a row of needles reciprocable with one of the compressors, and means for differentially and horizontally shifting the needles of a row into different positions, relatively to a mattress on the frame.
4. In a tufting machine, the combination of a supporting structure, a mattress-supporting frame mounted on the structure to move horizontally and rectilinearly, upper and lower reciprocable compressors carried by the structure and adapted to compress the mattress on the frame for the insertion of a row of tufting ties into the mattress, a row of needles reciprocable with one of the compressors, a vertically reciprocable support for the needles and compressors which are reciprocable therewith and means for differentially and horizontally shifting the needles of a row into different positions, relatively to a mattress on the frame, one of said compressors comprising members shiftable horizontally with the needles.
5. In a tufting machine, the combination of a supporting structure, a mattress-supporting frame mounted on the structure to move horizontally and rectilinearly, upper and lower reciprocable compressors carried by the structure and adapted to compress the mattress on the frame for the insertion of a row of tufting ties into the mattress, a row of needles reciprocable with one of the compressors, common reciprocable supporting means for the needles and the latter compressor, and means for slidably and horizontally shifting the supporting means to bring the needles of the row into different positions relatively to the mattress.
6. In a tufting machine, the combination of a supporting structure, a mattress-supporting frame mounted on the structure to move horizontally and rectilinearly, upper and lower reciprocable compressors carried by the structure and adapted to simultaneously compress the mattress on the frame for the insertion of a row of tufting ties into the mattress, reciprocable supporting means for one of the compressors, and a row of needles for simultaneously inserting a row of tufting ties, mounted on and reciprocable with

said supporting means, and means for conjointly shifting the needles on the support, and additionally shifting one of the needles relatively to the others.

7. In a tufting machine, the combination of a supporting structure, a mattress-supporting frame mounted on the structure to move horizontally and rectilinearly, upper and lower reciprocable compressors carried by the structure and adapted to simultaneously compress the mattress on the frame for the insertion of a row of tufting ties into the mattress, a reciprocable support for one of the compressors, a row of needles each for simultaneously inserting a row of tufting ties mounted on and reciprocable with said support, said support comprising slidably connected members on which the needles are mounted, and means for reciprocating the needles on the support and relatively shifting said members.

8. In a tufting machine, the combination of a supporting structure, a mattress-supporting frame mounted on the structure to move horizontally and rectilinearly, upper and lower reciprocable compressors carried by the structure and adapted to compress the mattress on the frame for the insertion of a row of tufting ties into the mattress, one of said compressors comprising a row of pairs of studs, a vertically reciprocable support for the studs and a row of reciprocable needles carried by the support and between the studs of each pair respectively, for simultaneously inserting a row of tufting ties.

9. In a tufting machine, the combination of a supporting structure, a mattress-supporting frame mounted on the structure to move horizontally and rectilinearly, upper and lower reciprocable compressors carried by the structure and adapted to compress the mattress on the frame for the insertion of a row of tufting ties into the mattress, one of said compressors comprising a pair of spaced bars and the other a row of pairs of studs, a vertically reciprocable support for the studs and a row of reciprocable needles carried by the stud-support between the studs of each pair respectively for simultaneously inserting a row of tufting ties, said needles being mounted to move with said studs.

10. In a tufting machine, the combination of a supporting structure, a mattress-supporting frame mounted on the structure to move horizontally and rectilinearly, upper and lower reciprocable compressors adapted to simultaneously compress the mattress on the frame for the insertion of a row of tufting ties, a row of needles provided with eyes for simultaneously inserting a row of tufting ties through the mattress, and reciprocable supporting means for the needles in which the needles are individually and yieldingly mounted and whereby the needles will be forced through the mattress when the supporting means is reciprocated but arrested when they encounter a solid obstruction in the mattress.

11. In a tufting machine, the combination of a supporting structure, a mattress-supporting frame mounted on the supporting structure to move horizontally and rectilinearly, upper and lower reciprocable compressors for the mattress adapted to simultaneously compress the mattress for the insertion of a row of tufting ties, a row of reciprocable needles provided with eyes for simultaneously inserting a row of tufting ties, reciprocable supporting means in which the needles are vertically slidably, and spring-snap devices for yieldingly retaining the needles in operative position on their supporting means and whereby

the needles will be held to pass through the mattress but will be arrested when they encounter a solid obstruction.

12. In a tufting machine, the combination of a supporting structure, a mattress-supporting frame mounted on the structure to move horizontally and rectilinearly, upper and lower reciprocable compressors carried by the structure and adapted to compress the mattress on the frame for the insertion of a row of tufting ties into the mattress, a series of combined sewing and compressing units each provided with a needle, one of the compressors comprising studs on the units, and a reciprocable support for said units along which they are longitudinally adjustable.

13. In a tufting machine, the combination of a supporting structure, a mattress-supporting frame mounted on the structure to move horizontally and rectilinearly, upper and lower reciprocable compressors carried by the structure 5 and adapted to compress the mattress on the frame for the insertion of a row of tufting ties into the mattress, a series of combined sewing and compressing units each provided with a needle, one of the compressors comprising studs on the 10 units, and a reciprocable bar on which said units are longitudinally adjustable to vary the spacing between them.

JOSEPH W. DROLL.

ALEX H. OLSON.
